CLAIM

The ornamental design for a rope-end buckle, as shown and described.

DESCRIPTION

FIG. 1 is a perspective view of a rope-end buckle, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of the rope-end buckle of FIG. 1 thereof; and,

FIG. 9 is a demonstration view showing the bottom portion of the buckle in an open position and the rope end knotted after passing through the rope-end buckle.

The broken line showing of rope is included for the purpose of illustrating environmental structure and forms no part of the claimed design.

The broken line showing of rope-end buckle is included for the purpose of illustrating portions of the article and forms no part of the claimed design.
